United States Patent Office

Des. 174,102
Patented Feb. 22, 1955

174,102

PENDANT OR SIMILAR ARTICLE

Samuel Stonberg, Merion, Pa.

Application June 14, 1954, Serial No. 30,961

Term of patent 14 years

(Cl. D45—17)

Fig. 1

To all whom it may concern:

Be it known that I, Samuel Stonberg, a citizen of the United States, residing at Merion, in the county of Montgomery, State of Pennsylvania, have invented a new, original, and ornamental Design for a Pendant or Similar Article, of which the following is a specification, reference being made to the accompanying drawing, forming part hereof.

I claim:

The ornamental design for a pendant or similar article, substantially as shown.
